United States Patent Office.

GEORGE WELLHOUSE, OF AKRON, OHIO.

Design No. 4,825, dated April 18, 1871.

DESIGN FOR A COOKING-STOVE.

The Schedule referred to in these Letters Patent and making part of the same.

To all whom it may concern:

Be it known that I, GEORGE WELLHOUSE, of Akron, in the county of Summit and State of Ohio, have invented a certain new configuration or Design for a Cook-Stove, of which the following is a description, reference being had to the accompanying photographic illustration.

The general outline of the design of this stove is similar to that of this class of stoves now in ordinary use, whereas the detail of the design varies in some important points considerably therefrom.

This stove is intended for burning either wood or coal, and, therefore, to burn wood of the ordinary wood-stove length, the fire-place or box A is made longer than that of the ordinary coal-stove, thereby making a projection of the ends of the fire-box beyond the sides of the stove, as shown in the illustration at A.

The projections in front, near the top of the stove, though common to coal-stoves, are not applied to a wood and coal-stove. In this particular my stove differs from others of this class.

Below the projections above referred to, and near the hearth, is a register, whereby the draught is admitted to or shut off from the lower side of the fire-grate, as shown in the illustration.

The upper one of the two small doors is that giving access to the fire-box, and is ornamented by a panel having thereon a human head wearing a crown. An

inner undulating border surrounds the head, and is inclosed by a plain heavy molding as an outer frame.

The two oven-doors are ornamented in the same way, having the same general character of expression.

The rear end of the top of the stove projects beyond the body, and from which proceeds the flue.

On each side thereof is a boiler-hole, represented as being closed by the covers, as are the four other holes in the top.

Below the projecting rear end referred to is a grated shelf attached to and projecting from the back of the stove.

The whole outline edge of the stove is finished in a bold plain molding, making a smooth, clean, and handsome finish, all of which several features specified make up a new and beautiful design, unlike that of any other of this class of stoves.

Claim.

What I claim as my improvement, and desire to secure by Letters Patent, is—

The design for a cook-stove, substantially as described and represented in and by the accompanying photographic illustration.

GEORGE WELLHOUSE.
